UNITED STATES PATENT OFFICE.

OSCAR L. OWEN, OF WHITINSVILLE, MASSACHUSETTS.

PATTERN MECHANISM OF LOOMS.

No. 904,495.

Specification of Letters Patent.

Patented Nov. 17, 1908.

Application filed September 28, 1906. Serial No. 336,523.

To all whom it may concern:

Be it known that I, OSCAR L. OWEN, a citizen of the United States, residing at Whitinsville, county of Worcester, and State of 5 Massachusetts, have invented certain new and useful Improvements in Pattern Mechanisms of Looms, of which the following is a full, clear, and concise specification.

My invention relates to the pattern mechanisms of looms, and consists of a simple and effective arrangement of the driving mechanism thereof, whereby the number of parts is reduced, and the shed-forming and drop-box pattern-chains may be jointly actuated in the normal operation of the loom, or manipulated independently of the loom in case the weaver wishes to adjust either of the chains separately or both together, as will be hereinafter fully described and more 20 particularly pointed out in the accompanying claims.

In the drawings forming a part hereof, only so much of the ordinary dobby-frame and associated parts is shown as is necessary 25 for illustrating the principle and application of my invention, and the said parts will be easily recognized by those familiar with this art.

Figure 1 is a side elevation of a portion of 30 a loom dobby, showing the shed-forming and shuttle-box pattern-chains arranged in accordance with my invention, but, for convenience, omitting the usual parts operated by said mechanisms; Fig. 2 is a plan view of 35 the parts shown in Fig. 1; and Fig. 3 is a side view of Fig. 1.

The dobby-frame is of usual construction secured to the loom frame A, and comprises, as usual, the two side frames A', A', in 40 which the shed-forming pattern shaft B is journaled and between which the pattern-chain drum B' and its chain C are carried. The pattern-chain shaft B protrudes at each end beyond the dobby-frame and at one end 45 is provided with an idly mounted worm-gear B² and a friction slip-clutch B³ held against the gear by a suitable spring. The worm D engaging the under side of gear B² is carried by a short shaft D' which is 50 geared to the crank-shaft E of the loom through the instrumentality of the sprocket connections D² and gears D³, D⁴ of usual arrangement. By means of this gearing the worm-gear B² thus constitutes a power 55 means for driving the pattern shaft B through the slip-clutch B³ above mentioned.

The shuttle-box pattern-chain F is carried by its chain-drum F' on the shaft G which is parallel with shaft B and, like it, journaled in the side-frames A', A' of the 60 dobby. The lifting levers F³ located above the shuttle-box pattern-chain are adapted to be operated in the well understood manner for controlling the position of the shuttle boxes by means of connections not shown in 65 the drawings. The shaft G is longer than the shaft B, so that the chain drum F' carried at its extremity, is offset from the other chain, as viewed from the end of the loom, and is likewise out of the way of the dobby 70 connecting rod D⁵ and other of the driving gearing ordinarily to be found at this side of the dobby frame.

At the opposite side of the dobby-frame the two shafts B and G are interconnected 75 by means of gearing which comprises a short shaft H appropriately journaled in brackets on the frame A' and carrying at each end the bevel gears H', H², which latter are respectively in mesh with the pinion B⁴ on shaft 80 B and pinion G⁴ on shaft G. The pinion H² is slidably mounted or splined upon its shaft so that it may be moved into and out of engagement with the gear G⁴, thus constituting a clutch between the two shafts B 85 and G, by means of which they may be connected or disconnected as desired. The shifting means for the clutch gear H² comprises a shifting lever K fulcrumed on a bracket K' with one end engaging an annular groove in the hub of pinion H² and the other end fashioned as a handle. A spring 90 detent K², of ordinary construction, is housed within the bracket adjacent to the fulcrum pin of the shifting lever K for retaining the same in either its connecting or disconnecting position. The shaft G is provided with a hand-wheel or knob G³, by means of which it may be manually rotated, and the shed-forming pattern-shaft B is also 100 provided with a means for manual operation in the form of a crank-wheel L which is somewhat larger than the hand wheel G³.

In the normal operation of the loom, and when employing the shuttle-box pattern-mechanism, the two shafts will be geared together as indicated in Fig. 2, so that the motion imparted, as above described, to the shaft B will be communicated by it to the shaft G. If it is desired by the weaver to 105 return this mechanism backwardly with respect to the rest of the loom, as in the case 110

of a mis-pick or a flaw in the weave or for any other cause, he may do so by turning the crank-wheel L in obvious manner, which produces corresponding rotation of both 5 chains. During this adjustment the clutch B³ will slip on the driving worm-gear B². Or, if he desires for special reasons to adjust one chain independently of the other, this may be done by opening the clutching 10 means of the interconnecting gearing. In cases where the shed-forming pattern-mechanism only is required for the work in hand, the shuttle-box mechanism may be disconnected and rendered inoperative by leaving 15 the clutching lever K in its open position.

It should be noted that the foregoing arrangement of the chains on two parallel shafts both carried by the dobby frame and of the hand wheels and clutch on the same 20 side of the said frame, is especially advantageous in respect of the ease and readiness with which either one, or both, may be manipulated by the weaver, and likewise that the simplicity of the connecting gearing, 25 which is also exposed to view, renders the apparatus easily understood by the weaver and therefore less likely to be improperly adjusted.

Having described my invention, what I 30 claim and desire to secure by United States Letters Patent is:

1. In a pattern-loom, a dobby-frame and a shed-forming pattern shaft journaled therein, a shuttle-box pattern shaft also 35 journaled in said frame, and gearing interconnecting said shafts, in combination with power means independent of said gearing, for driving one of said shafts, a clutch between said power means and the shaft which 40 it drives, means for disconnecting the aforesaid gearing and means for manually operating said shafts.

2. In a pattern loom, a dobby-frame, a 45 shed-forming pattern-shaft journaled there-

in, a shuttle-box pattern-shaft also journaled 45 in said frame, gearing interconnecting said two shafts located at one side of said frame and a clutch associated with said gearing, in combination with independent power means for driving one of said shafts and located 50 at the opposite side of the said frame, and a clutch between said power means and the shaft which it drives.

3. In a pattern loom, the combination of 55 the dobby-frame, two parallel shafts carried thereby and respectively arranged to drive the shed forming and the shuttle-box pattern chains, hand wheels for each said shaft on the adjacent ends thereof, gearing interconnecting said two shafts, and a power 60 driving means independent of said gearing and engaging the other end of one of said shafts, in combination with means for disengaging said interconnecting gearing.

4. In a pattern loom, a dobby comprising 65 two side frames adapted to accommodate the shed-forming pattern chain between them, a driving shaft for said chain journaled in said side frames, a driving shaft for the shuttle-box pattern mechanism also 70 journaled in said side frames, a clutch at one side of the dobby applied to one of said shafts and power means driving said shaft through said clutch in combination with interconnecting gearing between said two 75 driving shafts on the opposite side of the dobby, whereby the motion imparted to one is transmitted by it to the other, means for disconnecting said gearing and a hand wheel for each of said shafts. 80

In testimony whereof, I have signed my name to the specification in the presence of two subscribing witnesses.

OSCAR L. OWEN.
